UNITED STATES PATENT OFFICE

156,611

FENDER ORNAMENT

John L. Domann and John A. Domann,
South Gate, Calif.

Application April 29, 1949, Serial No. 2,335

Term of patent 3½ years

(Cl. D48—32)

To all whom it may concern:

Be it known that we, John L. Domann and John A. Domann, citizens of the United States of America, residing at South Gate, in the county of Los Angeles and State of California, have invented a new, original, and ornamental Design for a Fender Ornament, of which the following is a specification, reference being had to the accompanying drawings, forming a part thereof:

Figure 1 is a perspective view of a fender ornament showing our new design.

Figure 2 is a side elevational view thereof.

Figure 3 is an end elevational view.

We claim:

The ornamental design for a fender ornament, substantially as shown.

JOHN L. DOMANN.
JOHN A. DOMANN.
